UNITED STATES PATENT OFFICE.

JOHN R. MOORE, OF CHICAGO, ILLINOIS.

TOOL HOLDER.

1,423,245.

Specification of Letters Patent.

Patented July 18, 1922.

Application filed March 17, 1921. Serial No. 452,933.

To all whom it may concern:

Be it known that I, JOHN R. MOORE, a citizen of the United States, residing at Chicago, in the county of Cook and State of Illinois, have invented a new and useful Improvement in Tool Holders, of which the following is a specification.

My invention relates, more particularly, though not exclusively, to tool-holders for holding tools for cutting all kinds of threads, such as worm threads and acme threads. Furthermore, the invention has applicability to holders for shaper tools for cutting keyways and the like.

One of my primary objects is to provide a novel, simple and economical construction of tool-holder of the type adapting the portion of the holder carrying the tool to be adjusted to different angles relative to the work to be operated on, and which shall involve the minimum number of parts.

Another of my primary objects is to provide a novel, simple and inexpensive construction of tool-holder of the so-called spring type wherein the cutting tool is so supported that it bears yieldingly against the work and is adapted to be adjusted to vary the angle at which the tool extends relative to the work. A further object in this connection is to provide a construction of the character last stated, whereby the spring section of the holder may be adjusted, to cause the spring section to operate in line with the pressure exerted by the tool in operating on the work, in all the positions of angular adjustment of the tool relative to the work, thereby to insure equal pressure at both sides of the cutter.

Another primary object of my invention is to produce clean-cut and smooth threads on the work even when the latter is formed of relatively soft and inferior grades of metal, such as steel; and other objects as will be manifest from the following description.

Referring to the accompanying drawings: Figure 1 is a plan view of my improved tool-holder, and in connection therewith a bar shown as being operated on by a tool in the holder. Figure 2 is a view in side elevation of the holder of Fig. 1. Figure 3 is a longitudinal sectional view through the holder, the section being taken at the irregular line 3-3 on Fig. 4 and viewed in the direction of the arrows; and Figure 4 is a front end view of the holder.

I have chosen to illustrate my invention

as applied to a holder designed, more particularly, for holding a thread-cutting tool, the particular construction shown, and constituting the preferred embodiment of my invention, comprising a shank 5 at which the holder is adapted to be secured in position on the machine in connection with which it is used, as for example in a tool-post on a lathe, the forward end of the shank being provided with a pivot-stud 6 extending lengthwise of the shank and threaded at its outer end. Pivots supported on the stud 6 is a spring member, or head, 7 shown as of loop form and affording the legs 8 and 9 disconnected at their lower ends, but connected at their upper ends by the portion 10. The spring section 7 may be formed of any suitable material, preferably spring steel and affords, between the legs 8 and 9 a recess 11. The leg 9 contains an opening 12 through which the pivot-stud 6 extends and at which portion the section 7 is afforded pivotal support for the purpose of affording pivotal support of the section 7 on the shank 5. The threaded end of the pivot-stud extends into the recess 11 and has screwed thereon a nut 13 between which and the shouldered portion 14 of the shank, the spring section 7 is rigidly clamped, at its leg 9, to hold the section 7 in adjusted position on the shank 5, by tightening up the nut 13. The leg 8 is shown as containing a socket 15 adapted to receive the cutting tool, such as that represented at 16, the latter being rigidly held on the section 7 by means of a set-screw 17 screwing through an opening 18 in the leg and against the tool 16. The tool 16, may be of any desirable construction, the cutting edge thereof being represented at 19.

It will be understood from the foregoing that the angle at which the cutting edge 19 of the tool extends relative to the work, the latter being represented at 20, may be varied as desired by loosening the nut 13 and rotating the section 7 on the shank 5, and set in such adjusted position by tightening up this nut. Thus, in adjusting the section 7 to cause the tool to extend at its cutting edge 19 at right angles to the plane of the thread to be cut, the spring-supported leg 8 is caused to extend in a direct line with the pressure exerted against the tool in the cutting operation, regardless of the angle to which the section 7 is adjusted on the shank 5, and thus this leg will yield in such direct line,

with the result of the pressure at the opposite edges of the tool, in cutting the thread, being maintained uniform and thereby effecting the cutting of a clean and finished 5 thread on the work.

It may be further stated that, before commencing the cutting of the thread, the spring section 7 would be adjusted on the shank 5 at the pivot 6 to cause the cutting edge 19 to 10 extend at right angles to the plane of the threads of the lead-screw (not shown but commonly provided) which produces relative movement of the work and tool-holder in the operation of the machine with which 15 it would be used, it being preferred that a scale be provided on the holder for facilitating the proper setting of the section 7 relative to the shank 5. In the construction shown such a scale is provided at 21 on the 20 shank 5, it being graduated to degrees of a circle, and cooperating with this scale is a centralized mark 22, shown as a line, on the spring section 7.

While the invention has particular applicability to the cutting of threads, it may 25 be also applied to holders for shaping tools wherein, as for example in the cutting of keyways, it is desired to adjust the tool relative to the work to avoid rubbing contact of 30 the tool at its rear edge, or heel, against the walls of the grooves being cut.

Furthermore, it will be noted that the 35 holder is formed of comparatively few parts, thereby permitting of the ready assembling 40 thereof and the economical production of the device. In this connection it may be 45 stated that the features of the device whereby it may be produced very economically, are not limited to embodiment in a structure 50 wherein the section 7 is a spring section.

While I have illustrated and described a particular construction involving my invention, I do not wish to be understood as intending to limit it thereto as the same may 45 be variously modified and altered without departing from the spirit of my invention.

What I claim as new, and desire to secure by Letters Patent, is:

1. A tool-holder formed of sections by one 50 of which the holder is adapted to be supported, the other of said sections being a spring section adapted to support the tool, said spring section being adjustable upon the other section about an axis extending lengthwise of the latter, and means located at one end only of said first-referred-to section for 55 adjustably securing said spring section to be adjusted as stated to vary its inclination relative to the work.

2. A tool-holder formed of sections by one 60 of which the holder is adapted to be supported, the other of said sections being a spring section adapted to support the tool, and means located at one end only of said 65 first-referred-to section for adjustably piv-

oting said spring section thereto on an axis extending lengthwise of said first-referred-to section and adapting said spring section to vary its inclination relative to the work.

3. A tool-holder formed of sections by one 70 of which the holder is adapted to be supported, the other of said sections being a spring section adapted to support the tool, said spring section being of loop form and adapted at one leg thereof to support the 75 tool, and means located at one end only of said first-referred-to section and engaging the other leg of said spring section for adjustably securing the latter thereto and adapting said spring section to be adjusted 80 on an axis extending lengthwise of said first-referred-to section to vary its inclination relative to the work.

4. A tool-holder formed of sections by one 85 of which the holder is adapted to be supported, the other of said sections being a spring section adapted to support the tool, said spring section being of loop form and adapted at one leg thereof to support the 90 tool, and means located at one end only of said first-referred-to section and engaging the other leg of said spring section for adjustably pivoting securing the latter thereto on an axis extending lengthwise of said 95 first-referred-to section and adapting said spring section to be adjusted to vary its inclination relative to the work.

5. A tool-holder formed of sections by one 100 of which the holder is adapted to be supported, said section being provided at one end with a pivot stud extending lengthwise thereof, the other of said sections being a spring section adapted to support the tool, said spring section being supported on said 105 stud and adjustable about the latter to vary the inclination of the tool relative to the work.

6. A tool holder formed of sections at one 110 of which the holder is adapted to be supported, the other of said sections being supported on said first-referred-to section and adjustable thereon about an axis, said last-referred-to section containing a slot for a tool 115 extending lengthwise of said axis, with the upper wall of said slot substantially in alignment with said axis, a tool located in said slot and fitting against the upper and lower walls of said slot with its cutting edge substantially in alignment with said upper wall, and means securing said tool in said slot. 120

7. A tool-holder formed of a shank at which the holder is adapted to be supported and provided at one end with a threaded pivot-stud extending lengthwise thereof, and a spring member adapted to support a tool 125 pivotally supported on said stud.

8. A tool-holder formed of a shank at which the holder is adapted to be supported and provided at one end with a threaded pivot-stud extending lengthwise thereof, and 130

- a spring member of loop form adapted at one leg to support a tool and pivotally supported at its other leg on said stud.
9. A tool-holder formed of sections one of which contains a recess, and means connecting said sections together to permit of their relative adjustment on an axis at an angle to said recess, comprising a rotatable element in said recess and through the medium of which said sections are secured together in adjusted position.
10. A tool-holder formed of sections one of which contains a recess and an opening extending at an angle thereto, and means connecting said sections together to permit of their relative adjustment, said means extending through said opening and into said recess, and through the medium of which said sections are secured together in adjusted position.
11. A tool-holder formed of sections one of which contains a recess, and means connecting said sections together to permit of their relative adjustment on an axis at an angle to said recess, comprising a rotatable element in said recess and between which and the other of said sections the one of said sections containing said recess, is clamped.
12. A tool-holder formed of sections one of which contains a recess and an opening extending at an angle thereto, and means
- connecting said sections together to permit of their relative adjustment, said means extending through said opening and into said recess and comprising an element between 35 which and the other of said sections the one of said sections containing said recess, is clamped.
13. A tool-holder formed of sections one of which presents a pivot-stud threaded at 40 its outer end, the other of said sections containing a recess and an opening extending at an angle to said recess and opening into the latter, said stud extending through said opening and affording a pivot for said section containing said recess, and a clamping nut located in said recess and engaging the threaded end of said stud.
14. A tool-holder formed of sections one of which presents a pivot-stud threaded at 50 its outer end, the other of said sections being of spring material and of loop form and presenting a recess, one of the legs of said loop section containing an opening into which said stud extends to form a pivotal 55 support for said spring section, the other leg of said spring section being adapted to support a tool, and a nut located in said recess and screwed on said pivot-stud, for the purpose set forth.

JOHN R. MOORE.
